[57] CLAIM

The ornamental design for a display panel for a medical imager, as shown and described.

DESCRIPTION

FIG. 1 is an isometric view of a display panel for a medical imager showing our new design;

FIG. 2 is a front elevational view thereof;

FIG. 3 is a top plan view thereof, the bottom view is a mirror image;

FIG. 4 is a rear elevational view thereof;

FIG. 5 is a right side elevational view thereof, the left side elevational view is a mirror image; and,

FIG. 6 is a perspective view thereof, with the broken line showing of the medical imager being for illustrative purposes only and forming no part of the claimed design.
